G. P. REXROAT.
FEEDING APPARATUS.
APPLICATION FILED JULY 17, 1915.

Patented Oct. 5, 1915.

Inventor
G. P. REXRODT

for Watson E. Coleman

Attorney

UNITED STATES PATENT OFFICE.

GEORGE PORTER REXROAT, OF RODHOUSE, ILLINOIS, ASSIGNOR OF ONE-FOURTH TO
CHARLES T. BATES, OF RODHOUSE, ILLINOIS.

FEEDING APPARATUS.

1,155,684.

Specification of Letters Patent.

Patented Oct. 5. 1915.

Application filed July 17, 1915. Serial No. 40,451.

To all whom it may concern:

Be it known that I, GEORGE P. REXROAT, a citizen of the United States, residing at Roodhouse, in the county of Greene and 5 State of Illinois, have invented certain new and useful Improvements in Feeding Apparatus, of which the following is a specification, reference being had to the accompanying drawings.

10 This invention relates to improvements in feeding apparatus and has relation more particularly to a device of this general character especially designed to convey fuel from a source of supply and to properly deliver the same upon a fire bed; and it is 15 an object of my invention to provide an apparatus of this general character having novel and improved means whereby it may be adjusted into or out of operative position 20 with convenience and facility and whereby it may be conveniently operated in a manner to assure proper distribution of the fuel within the fire box.

The invention consists in the details of 25 construction and in the combination and arrangement of the several parts of my improved feeding apparatus whereby certain important advantages are attained and the device is rendered simpler, less expensive 30 and otherwise more convenient and advantageous for use, all as will be hereinafter more fully set forth.

The novel features of the invention will be 45 carefully defined in the appended claims.

50 In order that my invention may be the better understood, I will now proceed to describe the same with reference to the accompanying drawings, wherein—

Figure 1 is a view, partly in elevation and 40 partly in section, illustrating a feeding apparatus constructed in accordance with an embodiment of my invention, the coacting conveying mechanism being shown in fragment; Fig. 2 is a sectional view taken substantially on the line 2—2 of Fig. 1; Fig. 3 45 is a sectional view taken substantially on the line 3—3 of Fig. 1; Fig. 4 is a sectional view taken substantially on the line 4—4 of Fig. 1; and Fig. 5 is a sectional view taken 50 substantially on the line 5—5 of Fig. 1.

As disclosed in the accompanying drawings, F denotes a fire box of any ordinary or preferred construction and being provided in one of its walls with the fire door D. While the fire box F is herein disclosed

in a somewhat diagrammatic manner, I wish to state that my invention as herein embodied is particularly adapted for use in connection with locomotives, although my invention is capable of use with equal facility 60 in connection with fire boxes of general application.

1 denotes a table or platform operatively supported by the surface S through the medium of the legs 2 and resting upon the table or platform 1 is the casing 3 substantially circular in top plan and having positioned therein the rotor, herein disclosed as comprising a plurality of blades 4 radiating from the vertically disposed shaft 65 5 extending through the casing 3 at substantially its axial center and rotatably supported in any conventional manner by the structure comprised in the table or platform 1 and the supporting legs 2. The shaft 70 5 is operatively engaged, as at 6, with a driving shaft 7 of the engine or motor E which may be as desired, but herein disclosed as a steam operated type.

Extending from a side wall of the casing 80 3 to one side of its center is a discharge spout 8 of predetermined dimensions and having its free end portion circular in cross section and telescopically engaged by the delivery sleeve 9 which is capable of movement longitudinally of the spout 8 and axially thereof, said delivery sleeve or member being adapted for insertion within the fire box F through the door D thereof and also capable of sufficient movement away from the door D to permit the same being closed 85 in the regular way.

Pivottally engaged with the outer extremity of the sleeve or member 9 is the deflector member 10, the arms 25 being pivotally engaged at diametrically opposed points with said sleeve or member 9 and one of said arms 25 is provided with the extension 26 with which is operatively engaged the rod 27 also suitably anchored to the table 95 1, whereby it will be perceived that upon longitudinal movement being imparted to the sleeve or member 9 the deflector member 10 will be correspondingly rocked so that 100 as the member 9 is extended within the fire box the coal discharged therefrom will be directed downwardly.

28 denotes a rock shaft disposed transversely of the spout 8 and positioned therebelow, said shaft being operatively sup- 110

ported by the bearings 29 and one extremity of said shaft is provided with a rock arm 30 operatively engaged with the inner extremity of the sleeve or member 9 through the medium of the link 31 whereby it will be perceived that upon proper rotation of the shaft 28 longitudinal movement may be readily and conveniently imparted to the sleeve or member 9. The opposite extremity of the rock shaft 28 has pivotally engaged therewith the lever 32 movable in a direction longitudinally of the shaft 28 and provided with the latch mechanism 33 coacting with the rack 34 carried by said shaft 28 and said lever 32 is operatively engaged with the sleeve or member 9 through the medium of the rod 35 whereby it will be perceived that upon proper manipulation of the lever 32 the desired axial rotation may be given to the sleeve or member 9 and that the coaction between the latch mechanism 33 and the rack 34 serves to maintain said sleeve or member 9 in its various axial adjustments. It will also be perceived that the lever 39 affords a convenient means whereby the requisite axial rotation may be given to the rock shaft 28.

In communication with the casing 3 through the top thereof and at the side of the axial center of the casing with which the spout 8 communicates is the chute 17 into which is discharged the fuel carried by the conveyer 18 leading from a suitable source of fuel supply, said conveyer being herein disclosed as positioned within a suitable casing 19. As the fuel is delivered by the conveyer 18 within the casing 3 through the hopper 17, the blades 4 serve to throw the fuel through the spout 8 and the delivery member or sleeve 9 within the fire box F and the longitudinal and axial adjustment of the sleeve or member 9 together with the pivotal adjustment of the deflector member 10 serves to determine the portion of the fire bed to which the fuel is delivered. As herein disclosed, the upper shaft 20 around which the conveyer 18 passes is operatively connected, as at 21, with the driving shaft 7 of the engine or motor E whereby it will be perceived that said conveyer will be caused to operate in unison with the rotor or blades 4. It is also to be observed that the blades 4 are slotted, as at 22, or otherwise perforated in order to reduce to a minimum the blast of air forced through the chute 8 and the sleeve or member 9 so that the air admitted within the fire chamber during the feeding of the fuel will be substantially the same as would otherwise enter through the fire door D alone.

As herein disclosed, the operative connection 21 is a conventional sprocket chain passing around the sprockets 23 and 24 secured, respectively, to the drive shaft 7 of the engine or motor E and the shaft 20 of

the conveyer 18. While the driving shaft 7 may be operatively supported in any manner desired, I herein disclose the same as mounted in the bearing plates 1^a depending from the table or platform 1, as is believed to be clearly shown in Figs. 1, 2 and 4 of the drawings. This, however, does not constitute an essential feature of my invention and may be varied in accordance with the requirements of practice.

From the foregoing description, it is thought to be obvious that a feeding apparatus constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A feeding apparatus comprising a casing having a feed opening and provided with a discharge spout, a delivery member telescopically engaged with the discharge spout and capable of longitudinal movement and axial rotation, a rotor mounted within the casing, means for driving the rotor, a deflector member pivotally engaged with the outer extremity of the delivery member and capable of rocking movement relative to the discharge end of the delivery member, a stationary support, and a rod operatively engaged with the deflector and the stationary support whereby said deflector is automatically caused to move relative to the discharge end of the delivery member upon endwise movement of the delivery member.

2. A feeding apparatus comprising a casing provided with a discharge spout, a delivery member telescopically engaged with the discharge spout and capable of longitudinal movement and axial rotation, a shaft supported below the delivery member and disposed transversely thereof, a rock arm carried by the shaft, a link operatively connecting the rock arm and the delivery member, a lever pivotally engaged with the shaft and movable in a direction longitudinally thereof, coacting locking means carried by the lever and the shaft, and a rod operatively connecting the lever and the delivery member whereby axial rotation may be imparted to the delivery member.

3. A feeding apparatus comprising a casing having a discharge spout, a delivery member telescopically engaged with the discharge spout and capable of longitudinal movement, a stationary support, a deflector

member pivotally engaged with the outer end of the delivery member and adapted to overlie the discharge end thereof, said deflector member being provided with an extension, and a rod operatively engaged with said extension and the stationary support whereby the deflector member is moved relative to the discharge end of the delivery

member upon longitudinal movement of the delivery member.

10

In testimony whereof I hereunto affix my signature in the presence of two witnesses.

GEORGE PORTER REKROAT.
